UNITED STATES PATENT OFFICE.

WALLACE WILLIARD PARSONS, OF WASHINGTON, DISTRICT OF COLUMBIA.

RETAINING-KEY FOR LOCKING SPLIT BOLTS.

No. 859,103.

Specification of Letters Patent.

Patented July 2, 1907.

Application filed December 8, 1906. Serial No. 346,940.

To all whom it may concern:

Be it known that I, WALLACE WILLIARD PARSONS, a citizen of the United States, residing at Washington, in the District of Columbia, have invented certain new and useful Improvements in Retaining-Keys for Locking Split Bolts in Railroad Construction, Structural Ironwork, &c.; and I do hereby declare the following to be a full, clear, and exact description of the invention, such as will enable others skilled in the art to which it appertains to make and use the same.

The object, generally stated, of my invention, is the provision of a retaining-key for use in locking two-membered or split-bolts in railroad construction, structural iron-work, etc., which key shall operate to spread the ends of the bolt in the cone-shaped opening of a collar carried by the bolt, thus securely to lock the collar and, when the ends of the bolt have been closed over the key, firmly to lock the bolt.

A further object is so to form the key that, when driven down between the ends of the split-bolt, it may be held, with great pressure, against the collar, during the operation of closing the ends of the bolt over the key, obviating all tendency of "creeping," or backward or retrograde movement, of the key, during such operation of closing the ends of the bolt; fuller disclosure of this peculiar and efficacious formation of the key appearing hereinafter.

Another object is so to form the key that bolts of slightly different lengths may be locked by my key equally as well; fuller disclosure of this peculiar and efficacious formation of the key appearing hereinafter.

With these objects in view, the invention may be said to reside, comprehensively stated, in a retaining- or locking-key comprising two integral wedges placed base to base and coinciding, the bases being of different lengths, and the wedge with the shorter base being disposed between the ends of the longer base.

As a matter of further and specific improvement, the invention also resides in a key of the character just described, the wedge with the longer base being formed with its two sides in two inclined converging planes terminating in a plane surface parallel with the base.

Further details of construction will be fully herein-after disclosed in the specification.

In the accompanying drawing: Figure 1 is a transverse section through a railway rail and fish-plates, showing one application of my invention; and Fig. 2 is a perspective view of my invention.

Referring to the drawing, my locking-key is formed of two integral wedges placed base to base and coinciding, the bases being of different lengths, and the wedge with the shorter base being disposed between the ends of the longer base: A indicates one wedge, with a base a.

The top of this wedge is a flat surface a' in a plane parallel to the plane of the base. The wedge A is desirably of the same depth from end to end thereof. The re-

maining wedge a² has a shorter base than that of the wedge A and is disposed between the ends of the longer base a, the two bases coinciding, and the ends a⁴, a⁴ of the wedge A projecting beyond the sides of the wedge 60 a³. This wedge terminates in a sharp edge a⁵.

For one application of my invention in use, attention is directed to Fig. 1, in which B represents an ordinary railway-rail, C, C fish-plates, as usual, on each side thereof, and D a split- or two-membered bolt extending 65 through the rail and fish-plates, carrying a collar d provided, desirably, with a cone-shaped opening d² therethrough. The retaining-key of my invention is driven down between the two ends of the shank of the bolt, the portions of the wedge A which extend beyond the sides 70 of the shank of the bolt affording abutments against which a tool may be pressed firmly during the operation of closing the ends of the shank of the bolt over the wedge A, and whereby the said abutments are forced with great pressure against the collar, holding the same 75 tightly against the fish-plate. "Creeping" or, in other words, backward or retrograde movement of the wedge-key after it has been driven between the two members of the shank and during the operation of closing the ends of the shank of the bolt over the wedge A will be 80 entirely prevented; because these projecting ends of the wedge A, extending beyond the sides of the shank of the bolt, afford abutments against which an appropriate tool may bear with great pressure.

It will be recognized that it is important, for my purposes and the efficacious objects which I have in view, that the wedge A shall be of the same depth from end to end, throughout its entire extent; for, if the ends of the wedge A, projecting beyond the sides of the shank of the bolt, were provided with an upper curved or beveled surface, it would be impossible for a tool to bear 90 squarely and firmly against such projecting ends, and the tool would be liable to slide or slip off. A most efficient mechanism, or tool, for engaging with, or bearing against said projecting ends of the wedge A which extend beyond the sides of the shank of the bolt, is disclosed in my co-pending application for patent filed December 8, 1906, Serial No. 346,942, and entitled "Mechanism for locking bolts."

It will be observed, from the structure of the wedge A, that my locking-key may be used equally as well to lock bolts of slightly different lengths. A bolt may be of a length so that, when the ends of the shank are bent toward each other on the inclined sides of the wedge 100 A, the end of each member of the shank will terminate on a line with, or short of, the surface a'. The bolt will be securely locked. And a bolt having a slightly longer shank than the bolt just described may be locked equally as well; for, in this case, the end of each member of the shank will project somewhat beyond the 105 surface a' of the wedge A, and may be bent together or closed on such surface; or the projecting ends of such 110

shank may be left as shown in Fig. 1 of the drawing. But, on the other hand, if my wedge A terminated in a sharp edge (such as the edge of wedge a^2), then it would be possible to use only a bolt the ends of the shank of which would terminate on a line with, or short of, such edge; because, if a bolt of slightly longer shank were attempted to be used, then the ends of the shank would meet beyond the line of the edge described, the consequence of which would be that the bolt and collar 5 would not be locked, as the shock and jar of passing trains would cause "creeping", or backward or retro-grade movement, of the retaining-key, and the whole structure would work loose. Wherefore, I consider my peculiar formation of retaining-key, whereby a portion 10 of the wedge A projects beyond each side of the shank affording abutments for the purpose described, and whereby there is provided a top surface a' on the wedge A, also for the efficacious purpose above described, as material, important, and valuable features of novelty 15 and invention.

Having thus fully described my invention, what I claim as new, and desire to secure by Letters-Patent, is:

1. The combination with a bolt having a split shank, of a collar disposed around the shank, and a key, comprising two wedge-shaped portions united base to base, adapted to be forced between the members of the shank and to extend within the collar, the outer end of the key extending laterally of the shank, to form a bearing surface for a securing tool, and having shoulders adapted to bear upon the collar. 2

2. The combination with a threadless bolt having a split shank, of a collar disposed around the shank, and a key, comprising a portion adapted to be forced between the members of the shank and to extend within the collar, and shoulders formed on the key and bearing upon the collar, the outer end of the key extending laterally of the shank. 3

In testimony whereof, I affix my signature, in the presence of two subscribing witnesses.

WALLACE WILLIARD PARSONS.
